UNITED STATES PATENT OFFICE.

STERLING T. PLAYFORD, OF ELGIN, ILLINOIS.

FUEL-MIXER FOR EXPLOSIVE-ENGINES.

1,086,211.

Specification of Letters Patent.

Patented Feb. 3, 1914.

Application filed May 26, 1913. Serial No. 770,028.

To all whom it may concern:

Be it known that I, STERLING T. PLAYFORD, a citizen of the United States, residing at Elgin, in the county of Kane and State of Illinois, have invented a new and useful Fuel-Mixer for Explosive-Engines, of which the following is a specification.

The present invention appertains to fuel mixers for internal combustion engines, and aims primarily to provide a novel and improved device of that character adapted for interposition between the carbureter and intake manifold and operable to efficiently mix the gases proceeding from the carbureter with the intake manifold, as well as breaking up any drops or particles of fuel and arresting any foreign or extraneous particles which may have passed through the carbureter.

As a more specific object, the present invention aims to provide a device of the nature indicated wherein the gases will be constrained to pass around a sharp or knife edge, thereby chopping or breaking up the drops of fuel which may have been carried from the carbureter with the gases, and to also arrest foreign particles that may have passed through the carbureter.

It is also within the scope of the invention to provide an extremely simple, compact and inexpensive device of the character specified, which shall be serviceable, convenient and efficient in its use.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

The invention has been illustrated in its preferred embodiments in the accompanying drawing, wherein similar reference characters have been employed to denote corresponding parts, and wherein:

Figure 1 is a fragmental perspective of one half of the device, the two halves being symmetrical. Fig. 2 is a bottom view of the device with the bottom removed. Fig. 3 is a view similar to Fig. 1 of a modification. Fig. 4 is a sectional view taken on the line 4-4 of Fig. 3. Fig. 5 is a view similar to Figs. 1 and 3 of a second variation. Fig. 6

is a sectional view taken on the line 6-6 of Fig. 5.

In carrying out the invention, reference being had in detail to Figs. 1 and 2, there is provided a mixing chamber 1, which, as 60 illustrated, is cylindrical and relatively shallow in order that it may be readily clamped between the carbureter and inlet branch of the intake manifold of an internal combustion engine. The mixing chamber 65 embodies the rim 2 having the integral top 3 and the bottom 4 engaged to the rim 2, the edge of the rim being preferably provided with a rabbet 5 into which the bottom 4 is threaded.

The mixing chamber 1 is provided with eccentric outlet and inlet ports or openings 6 and 7 in its top and bottom respectively, and the rim 2 is provided with an internal annular groove 8 approximately midway between the top and bottom. The ports 6 and 7 are adapted to register with the inlet branch of the intake manifold, and the outlet of the carbureter, respectively, in order that the gases proceeding from the carbureter may pass through the mixing chamber to the intake manifold.

A baffle plate 9 is disposed within the mixing chamber 1 between the ports 6 and 7, this baffle plate having one edge curved to 85 conform to the curvature of the rim 2, and the said edge being engaged in the groove 8 to maintain the baffle plate in position. The other or free edge of the baffle plate is curved so as to provide a crescent-shaped 90 opening 10 between it and the respective side of the rim 2. The free edge of the baffle plate 9 is deflected or bent downwardly slightly and sharpened, as at 11, to provide a depending knife edge over which 95 the gases are constrained to pass.

The rim 2 of the mixing chamber is preferably provided with an air inlet 12 adjoining the port 7 and below the baffle plate 9, the said inlet or aperture admitting air, 100 and being particularly useful when the air adjustment of the carbureter is insufficient. This air inlet may be dispensed with when the gas proceeding from the carbureter has a sufficient body of air.

For purpose of clamping the mixing chamber between the flanges of the carbureter and the inlet branch of the intake manifold, bolt holes 13 are provided in the top and bottom of the case and in the baffle 110

plate 9 through which the bolts may be passed which connect the said flanges. It will be evident that the mixing chamber may be readily interposed between the carburetor and the intake manifold, no detailed description or illustration thereof being deemed necessary.

In operation, the gases proceeding from the carburetor and passing through the mixing chamber will be constrained to follow a tortuous path from the port 7 over the knife edge 11 and thence to the port 6, in order that the gases will pass in a relatively wide path over the said knife edge to chop or break up the stray drops of fuel which may have been carried from the carburetor by the gases. In this manner, the knife edge of the baffle plate will break up any stray drops of fuel, and will further arrest any foreign particles which may have been carried through the carburetor. The baffle plate also has the function of mixing the carbureted gas, the device, as a whole, operating to thoroughly mix the gases so as not only to form a perfect gas for combustion within the cylinders, but to save fuel and increase the power. The drops of fuel being broken up will enrich the gas, so as not only to save fuel and increase power, but to eliminate the deposit of carbon on the valves and within the cylinders, as is customary due to the presence of drops of fuel in the combustible gas. It is to be understood that the present device may be employed in connection with any particular fuel, such as gasoline, kerosene, alcohol and the like, and may be employed in connection with various internal combustion engines, such as automobile, marine and the like.

When the air inlet valve is employed, it will be observed that an additional supply of air will be admitted, due to the suction created within the cylinders, in order that this additional supply of air will be thoroughly admixed with the carbureted air to form a more perfect combustible gas.

In the form illustrated in Figs. 3 and 4, the lower end of the inlet branch of the manifold M is provided with an enlarged portion 1' forming a mixing chamber. A coupling member 4' is threaded into the lower portion of the enlargement 1' for attachment to the carburetor, the coupling 4' being provided with a flange having bolt openings 13' for the attachment of the coupling to the carburetor. The enlargement 1' is provided with a plurality of internal annular grooves 8' with which the semi-circular baffle plates 9' are engaged. The alternate baffle plates 9' are reversed or staggered in order that their free edges will lie in a common plane cutting the axis of the enlargement 1', the free edges 11' being downturned and sharpened. It will be evident that the baffle plates may be readily inserted

and snapped into the respective grooves 8', and may be turned to their proper positions with respect to each other. The enlargement 1' may also be provided with the air inlet 12' in one side below the lowermost baffle plate 9', if desired.

The operation of the modification illustrated in Figs. 3 and 4 is similar to the form illustrated in Figs. 1 and 2, the gases passing in a tortuous path over the knife edges 11' to carry out the functions desired. The latter form is desirable in some instances, in that it permits the present device to be incorporated in the intake manifold, although the first mentioned form is desirable in other instances, in that it may be interposed between the carburetor and intake manifold of engines now in use.

In the variation illustrated in Figs. 5 and 6, the lower end of the intake manifold M is enlarged to provide the mixing chamber 1'' similar to the mixing chamber 1' above described. The mixing chamber 1'' embodies the rim 2'' having the top 3''. The bottom 4'' is threaded into the rim 2'' and has attached thereto a pipe 7'' adapted to be connected to the carburetor. The rim 2'' is provided with the internal annular groove 8''. The baffle plate 9'' is circular, but of slightly smaller diameter than the rim 2'', the baffle plate having a plurality of projections 9''a engaging within the groove 8'' to maintain the baffle plate 9'' in position. The said baffle plate 9'' is disposed concentrically within the mixing chamber and provides a plurality of arcuate openings 10'' adjoining the rim 2'' and between the projections 9''a. The free edges 11'' of the baffle plate 9'' are downturned and sharpened to carry out the desirable functions above pointed out. The pipe 7'' may be provided with an air inlet 12'' directly below the bottom 4'' and the members 3'', 4'' and 9'' may be provided with the bolt holes 13'' for attaching the mixing chamber to the carburetor or other part of the engine. The functions of the variation just described are the same as those of the above described forms, the two forms illustrated in Figs. 3 and 5 somewhat resembling each other, in that they are each incorporated with the intake manifold.

If desired, the mixing chamber and baffle plate may be cast integrally with the portion of the carburetor so that it will be understood that the device may be attached to either the intake manifold or the carburetor. It is also possible to construct the device of one casting, so that this may be disposed between the carburetor and intake manifold.

Having thus described the invention, what is claimed as new is:—

1. A device of the character described embodying a mixing chamber adapted to be

interposed between the carbureter and intake manifold of an internal combustion engine, and a baffle plate secured within the mixing chamber, to constrain the gases to

5 pass over certain edges of the baffle plate, said edges being bent and sharpened.

2. In a device of the character described, a mixing chamber adapted to be interposed between the carbureter and intake manifold

10 of an internal combustion engine, and a baffle plate disposed within the mixing chamber to constrain the gases to pass over

certain of its edges in a tortuous path, said edges being bent and sharpened, and the mixing chamber being provided with an air inlet below the baffle plate.

In testimony that I claim the foregoing as my own, I have hereto affixed my signature in the presence of two witnesses.

STERLING T. PLAYFORD.
